Samuel Ladd of Waltham Massachusetts

Letters Patent.

The schedule referred to in these Letters Patent and making part of the same containing a description in the words of the said Samuel Ladd himself of his improvement in the Hollow cylindrical Flyer for Spinning.

To all to whom these presents shall come. Be it known that I Samuel Ladd of Waltham in the County of Middlesex and State of Massachusetts, have invented a new and useful improvement in the method of manufacturing yarn and thread with the use of hollow cylindrical flyers; and that the following is a full and exact description thereof. The drawing numbered 1 shows annexed especially the machinery used for manufacturing of an Ethier. The part of the drawings. No. 1. A. is a perpendicular spindle around which the hollow cylindrical flyer, revolves B. represents the flyer D. is the whirb to receive the band or belt which cause the flyer to revolve E. the part contiguous to the spindle called the bushing with which the flyer revolves F. a cylindrical tube on which the bushing rests, G especially the yarn or thread passing down from the spinning through the rollers H. I. L. and the guide K. L. also through the side of the flyer on the spool C. M. all. is a stationary rail in which the tube F. is fixed. N. is a movable rail to let rise and fall the spool C. and K. is a device to keep the spindle in its place.

What I claim as my own invention and not previously known in the above described machine is the part marked B. Flyer Ladd's Patent Hollow cylindrical Flyer. The advantage of

of the above named flys are over those now in use are that the cylindrical flys move without any impediment from the wind and protect the grain or thresh from dust, and the sun power will move the cylindrical flys with greater speed than any other kind now in use, which cylindrical flys are made of wood or ~~metallic~~ substances.
